[57] CLAIM

The ornamental design for an ornament for footwear, as shown and described.

DESCRIPTION

FIG. 1 is a side elevational view of an ornament for footwear showing my new design;

FIG. 2 is a top left rear perspective view thereof; and, FIG. 3 is a sectional view taken along line 3—3 as shown in FIG. 1.

The broken line showing of a right shoe in FIG. 1 is for illustrative purposes only and forms no part of the claimed design.
